Inventor:
Ralph Shurtleff
Cook & McCauley Mfg.

UNITED STATES PATENT OFFICE.

RALPH SHURTLEFF, OF CHICAGO, ILLINOIS.

APPARATUS FOR AND METHOD OF MOLDING.

Application filed November 19, 1921. Serial No. 516,271.

To all whom it may concern:

Be it known that I, RALPH SHURTLEFF, a citizen of the United States of America, and a resident of Chicago, in the county of 5 Cook, in the State of Illinois, have invented certain new and useful Improvements in Apparatus for and Methods of Molding, of which the following is a full, clear, and exact description, reference being had to 10 the accompanying drawings, forming a part of this specification.

This invention relates to improvements in apparatus for and methods of molding, and has for its object the production of a 15 simple apparatus and method for molding articles that cannot be readily molded by the methods heretofore in general use.

In following the ordinary methods, considerable difficulty has been experienced in 20 molding from irregular patterns which cannot be readily withdrawn from the sand. One class of castings of which the above is true is metallic shoe heels, and such articles can be easily and quickly molded in accordance with this invention.

The method heretofore pursued in the 25 molding of metallic shoe heels involved a great amount of hand work which can only be performed by an expert molder, and only a comparatively few heels could be formed in a single flask due to the inability to properly ram the sand about the patterns.

The present invention includes a flask 30 which is so arranged that the sand may be forced into said flask from the sides, as well as from the top and bottom, so the sand can be very tightly packed around the pattern members within the flask.

Briefly stated my improved flask prefer- 35 ably comprises a cope, a drag, and a cheek interposed between said cope and drag. The cope and drag may be of the usual form, i. e., top and bottom receptacles into which the sand is forced in the usual manner. The 40 cheek preferably comprises a receptacle having sand receiving openings at its sides, and at one of its ends, and it preferably includes upper and lower match plates separated from each other to provide a sand-receiving 45 space between them. Each of said match plates may be provided with rows of pattern members which extend into the sand-receiving space. The side and end sand-receiving openings permit the sand to be

forced into this space and around the pattern members therein. 55

With the foregoing and other objects in view, the invention comprises the novel construction, combination and arrangement of parts hereinafter more specifically described 60 and illustrated in the accompanying drawings wherein is shown the preferred embodiment of the invention. However, it is to be understood that the invention comprehends changes, variations and modifications 65 which come within the scope of the claims hereunto appended.

Fig. I is a transverse section through a flask made in accordance with my invention, the sand in the cope, drag and cheek being 70 rammed and the match plates being shown between the cope and drag.

Fig. II is a view similar to Fig. I showing the flask as it appears after the match plates and sprue pattern have been removed. 75

Fig. III is a plan of the flask with the cope removed and with parts of the upper match plate broken away.

Fig. IV is a perspective, on a small scale, 80 of the cheek frame.

In the drawings A designates the flask which comprises a cope B, which is of the usual form, i. e., a topless and bottomless boxlike body into which sand is forced onto the pattern member contained therein, and 85 a drag C similar to the cope B which is also adapted to receive sand forced into and around a pattern member contained therein.

Interposed between the cope B and the drag C in the assembled flask is a cheek 90 D which includes a frame D' (Fig. IV) composed of transverse end members 1 and pairs of longitudinal side members 2 secured to said end members 1. Said frame D' is provided with dowels 3 and recesses 95 3' whereby said frame is interlocked with the cope B and drag C when the flask is in an assembled condition.

Interposed between the cope B and the frame D' is an upper match plate 4 which 100 is provided on its upper and lower sides with rows of pattern members 5. A pattern member 6 is also provided on said upper match plate to form the gate 7 and part of the sprue 8, the upper portion of said 105 sprue being formed by a separate pattern member 9.

10 designates a lower match plate which

in so far as the plate itself is concerned is a counterpart of the match plate 4, and is provided with rows of pattern members 11 which extend from said plate 10 and 5 meet the pattern members 5.

To insure against displacement of the match plates 4 and 11 with relation to their associated parts I provide each of said match plates with dowels 12 (Figs. I and 10 II) which are adapted to enter suitable recesses formed in said associated parts, and as a precaution against displacement of said match plates with relation to one another I provide each pattern member 5 of the up- 15 per match plate 4 with a dowel 13, and each pattern member 11 of the lower match plate 10 with a recess 14 which is adapted to receive the dowel 13. The dowels 13 and the recesses 14 are arranged on the 20 meeting faces of said pattern members 5 and 11 so that when the flask is assembled the danger of the match plates moving with relation to one another is eliminated.

As an illustration of a suitable means for 25 forcing sand between the match plates 4 and 10 and into engagement with the pattern members thereon, I have shown members 15, although it is to be understood that the invention is not limited to any particular means for forcing sand into a flask. The members 15 are adapted to enter the sand-receiving openings 16 in the sides of the frame D'.

As is shown in the drawings, the pattern 30 members on the match plates are in rows and it would be a rather difficult matter to force sand from the sides of the cheek, between the individual pattern members and into the open center between said rows of 40 said pattern members. Therefore, to insure the sand being tightly packed within this open center, I may employ a rammer 17 which is adapted to extend into the cheek D through a sand receiving opening 18 in 45 one of the end members 1 of the frame D'. By the use of this rammer 17, the sand introduced through said sand-receiving opening 18 may be tightly rammed in the cavity between the rows of pattern members.

In the practical use of my invention the 50 cope, the drag, and the cheek are assembled as shown in Fig. I with the match plates in place. The sand is then forced into the cope and drag in any suitable manner. The rammer 17 is passed through the opening 18 to serve as a filler between the rows of patterns, and sand is then introduced 55 through the openings in the sides of the cheek frame D' and packed tightly around the pattern members in the cheek. It will be observed by referring to Fig. I that when the sand is being forced into the cheek D from the sides thereof that the rammer 60 17 is in place in said cheek and will act 65

as a solid backing against which said sand may be forced, to tightly pack said sand on each side of said rammer 17. After the sides of the cheek D have been tightly rammed, the rammer 17 is withdrawn 70 and sand introduced through the opening 18 and this sand is tightly packed in place by the reciprocation of said rammer 17, during which operation the members 15 are allowed to remain in the 75 position in which they are shown in Fig. I to avoid disturbance of the sand that has already been packed in the sides of the cheek.

The ramming is now complete and the 80 sprue pattern 9 may be removed from the cope and said cope lifted from the match plate 4, after which said match plate 4 may be lifted from the lower match plate, thereby drawing the pattern members 5 thereon 85 from the sand in said cheek. The cheek frame D' from which the members 15 have previously been removed is now lifted from the lower match plate 10 and said match plate 10 removed from the drag.

A reassembly after the removal of the match plates will place the flask in the condition shown in Fig. II, and said flask is ready for the pouring of the metal. The intermediate bodies of sand, which are 95 molded between the match plates, then lie between and in contact with the sand in the cope and drag.

I claim:

1. In a molding apparatus, a flask comprising a cope, a drag, and a cheek between said cope and drag, said cope, drag and cheek having flat marginal faces and said cheek comprising upper and lower match plates and pattern members separating said match plates, said cheek being provided with 100 an opening at one of the flat marginal faces thereof, and means whereby sand is forced through said opening, between said match plates and into engagement with said pattern members.

2. In a molding apparatus, a flask comprising a cope, a drag, and a cheek between said cope and drag, said cope, drag and cheek having flat marginal faces and said cheek comprising upper and lower match plates, pattern members separating said match plates, means whereby said pattern members are interlocked with each other, said cheek being provided with an opening 105 at one of the flat marginal faces thereof, and means whereby sand is forced through said opening, between said match plates into engagement with said pattern members.

3. In a molding apparatus, a flask comprising a cope, a drag, and a cheek between said cope and drag, said cope, drag and cheek having flat marginal faces and said cheek comprising upper and lower match plates, pattern members separating said 110

match plates, and means comprising dowels projecting from the pattern member of one match plate and extending into the pattern member of the other match plate whereby 5 said pattern members are interlocked with each other, said cheek being provided with an opening at one of the flat marginal faces thereof, and means whereby sand is forced through said opening and between said 10 match plates to engage said pattern members.

4. In a molding apparatus, a flask comprising a cope, a drag, and a cheek between said cope and drag, said cheek comprising 15 upper and lower match plates, pattern members separating said match plates, the pattern member of said upper match plate being adapted to be seated upon the pattern member of the lower match plate, means 20 whereby said pattern members are interlocked with each other, and means whereby sand is forced into one of the sides of said flask and between said match plates to engage said pattern members.

25 5. In a molding apparatus, a flask comprising a cope, a drag, and a cheek between said cope and drag, said cheek comprising an upper match plate member closing the bottom of the cope, a lower match plate 30 member closing the top of the drag and pattern members separating said match plate members, said flask being provided with a sand-receiving opening between said match plate members at one of its sides, and means 35 whereby sand is forced into said opening between said match plate members and into engagement with said pattern members.

6. In a molding apparatus, a flask comprising a cope, a drag, and a cheek between 40 said cope and drag, said cheek comprising upper and lower match plates and rows of

pattern members separating said match plates, said flask being provided with sand-receiving openings between said match plates at one of its sides and at one of its 45 ends, and means whereby sand is forced into said openings, between said match plates and into engagement with said pattern members.

7. In a molding apparatus, a flask comprising a cope, a drag, and a cheek between said cope and drag, said cheek comprising upper and lower match plates and rows of 50 pattern members separating said match plates, said flask being provided with sand 55 receiving openings between said match plates at one of its sides and at one of its ends, and means whereby sand is forced into said openings.

8. The method of molding shoe heels 60 which comprises forming upper and lower match plate members with shoe heel pattern members between them, interposing said match plate members between a cope and a drag so as to completely close the top of the 65 drag and the bottom of the cope, said match plates being arranged in such positions that the pattern members of the upper match plate rest upon the pattern members of the lower match plate, forcing sand into the 70 cope and drag and into engagement with the respective match plate members, forcing sand through opposite sides of the flask and into engagement with opposite sides of said 75 pattern members, removing the match plate members and pattern members from the cope and drag, and reassembling the flask with the last mentioned sand between the cope and drag.

In testimony that I claim the foregoing I 80 hereunto affix my signature.

RALPH SHURTLEFF.
